UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, LONDON, ENGLAND.

ORDNANCE.

1,386,460.

Specification of Letters Patent. Patented Aug. 2, 1921.

Application filed November 11, 1918. Serial No. 262,086.

To all whom it may concern:

Be it known that we, Sir ARTHUR TREVOR DAWSON, knight, and Sir GEORGE THOMAS BUCKHAM, knight, both subjects of the King of Great Britain, residing at Vickers House, Broadway, Westminster, in the county of London, England, have invented certain new and useful Improvements in or Relating to Ordnance, of which the following is a specification.

This invention relates to ordnance, particularly anti-aircraft ordnance, having an independent line of sight and provided with vertical deflection gear for correcting the angle of tangent elevation for a target advancing toward or receding from the gun position.

According to the invention the vertical deflection gear is mounted on the gun carriage and operates through differential gearing to effect relative movement between the sight and the gun so as to correct for an advancing or a receding target, this differential gearing being also operated by the pointing gear to move the gun and the sight together in keeping the sight on the target. In this manner the vertical deflection gear remains in the same position whatever the angle of elevation of the gun may be.

In order that the said invention may be clearly understood and readily carried into effect, we will describe the same more fully with reference to the accompanying drawings, in which:

Figures 1 and 2 are elevations showing a constructional form of the invention as viewed from the left hand side and the right hand side of the gun, and Fig. 3 is a diagrammatic view of certain of the gears shown in Fig. 1.

A is the gun carriage, B, B' are the sights, B' is the sight carrier, B² the sight bracket, and B³ the toothed elevating arc attached to the sight bracket. C is the double crank hand lever of the pointing gear, this gear comprising a pinion c^x carried by a shaft c^{xx} Fig. 3 meshing with a toothed arc C^x attached to the gun cradle as is well understood. E is the hand wheel of the vertical deflection gear and E^x the vertical deflection dial, both the hand wheel and the dial being mounted on a bracket E⁰ attached to the gun carriage. F is the aforesaid differential gearing mounted in a casing F^x attached to the gun carriage.

In the example shown the pointing hand lever C drives a shaft C' operating through the bevel wheels c, c' (or through a worm and worm wheel) upon the differential gearing F which is also operated upon through a worm e and a worm wheel e' by a shaft E' driven from the vertical deflection hand wheel E. Leading from the said differential gearing is a shaft F' carrying a worm f' meshing with the sight elevating arc B³ which is in the form of a worm wheel segment. The said elevating arc is thus moved by the pointing hand lever C and by the vertical deflection hand wheel E either independently or simultaneously as the case may be. The worm G (Fig. 3) is the worm of the ranging gear, this worm meshing with a worm wheel G' with which, and with the shaft c^{xx} and a worm wheel C^x driven by the worm c^x of the pointing gear, is associated a differential gear G².

G³ (Fig. 1) is the handwheel of the ranging gear and G⁴ (Fig. 1) is the dial of this gear. It will be understood that the ranging gear operates through the differential gear G² to elevate the gun with respect to the sight.

What we claim and desire to secure by Letters Patent of the United States is:

1. In ordnance, the combination with the gun, the gun carriage and the sight, of pointing gear for elevating the gun and the sight together, ranging gear for elevating the gun with respect to the sight and means additional to said ranging and pointing gears and mounted on the carriage for correcting the sight line in a vertical plane for an advancing or receding target.

2. In ordnance, the combination with the gun, the gun carriage, the sight, the pointing gear for elevating the gun and the sight together, and the ranging gear for elevating the gun with respect to the sight, of means additional to said ranging and pointing gears and mounted on the carriage for effecting relative movement in elevation between the sight and the gun to correct for an advancing or a receding target and differential gearing operated by said means and also by the pointing gear.

3. In ordnance, the combination with the gun, the gun carriage, the sight, the pointing gear for elevating the gun and the sight together, and the ranging gear for elevating the gun with respect to the sight, of means

105

110

additional to said ranging and pointing gears and mounted on the carriage for moving the sight in elevation with respect to the gun to correct for an advancing or a receding target and differential gearing operated by said means and also by the pointing gear.

4. In ordnance, the combination with the gun, the gun cradle, the gun carriage, the sight and the pointing gear for elevating the gun and the sight together, of a vertical de-

flexion operating device mounted in a fixed position on the carriage, a rotary shaft, means whereby rotation of said shaft adjusts the sight in elevation and differential gearing interposed between said device and said shaft and also between said pointing gear and said shaft.

ARTHUR TREVOR DAWSON.
GEORGE THOMAS BUCKHAM.
